Patented Nov. 21, 1916.

UNITED STATES PATENT OFFICE.

CHARLES McLAY, OF MELVILLE, SASKATCHEWAN, CANADA.

WRENCH.

1,205,911.

Specification of Letters Patent.

Patented Nov. 21, 1916.

Application filed January 4, 1916. Serial No. 70,099.

To all whom it may concern:

Be it known that I, CHARLES McLAY, a subject of the King of Great Britain, residing at Melville, in the Province of Saskatchewan and Dominion of Canada, have invented new and useful Improvements in Wrenches, of which the following is a specification.

The present invention relates to improvements in the construction of wrenches.

10 In carrying out my invention it is my purpose to construct a wrench including a stationary and a movable jaw, and commonly known as a monkey wrench, with simple, cheap and effective means for locking the movable jaw upon the shank of the stationary jaw.

With the above and other objects in view, the improvement resides in the construction, combination and arrangement of parts set 20 forth in the following specification and falling within the scope of the appended claim.

In the drawing: Figure 1 is a view of a wrench constructed in accordance with the present invention, the carriage of the movable jaw being shown in section to illustrate the locking elements arranged thereon, Fig. 2 is a sectional view approximately on the line 2—2 of Fig. 1, Fig. 3 is a perspective view of a spring, Fig. 4 is a similar view 30 of the actuating lever and the pawl arranged thereon, Fig. 5 is a similar view of a member which may be employed for bridging the yoke members of the removable jaw or for partially closing the channel in the shank or 35 carriage of the movable jaw.

Referring now to the drawings in detail, the numeral 1 designates a stationary jaw that is provided with the usual shank 2 that has one of its edges provided with transverse 40 teeth 3, and the numeral 4 designates the handle for the shank. The movable jaw is indicated by the numeral 5 and includes a shank or carriage 6 as well as yokes 7—7 which straddle the shank 2 of the stationary 45 jaw. The carriage 6, in the present instance is provided with an elongated slot 8 which may communicate with the yokes 7, and the top of the slot 8 may be partially closed by a longitudinally extending strip 9 that is 50 connected thereto in any desired or preferred manner. The strip 9 has one of its edges formed with a curved depression 10 and its opposite edge at a suitable distance away from the depression provided with a 55 notch 11. This notch 11 is adapted to re-

ceive one of the offset ends 12 provided upon one of the angular arms 13 of a spring 14. The spring includes a coil or body portion 15 which rests within the depression 10 of the member 9. The coils or convolutions 15 of the spring also serve as a fulcrum point to receive an arcuate member 16 provided in a lever 17 that is arranged in the slot 8 and which has its tail portion projecting through the slot. This lever 17 has the edge 60 opposite that fulcrumed upon the spring 14 provided with a notch 18 disposed substantially diametrically opposite the notch 11 of the member 9 and the said notch is adapted to receive the second and offset end 19 of 70 the second angular arm 20 of the spring 14.

The numeral 21 designates a toothed dog that is pivotally secured to the lever 17 and which is adapted to be arranged at the end 75 wall provided by the slot 8 and the inner end of the member 9 and thereby projected to contact between the teeth 3 of the shank 2.

From the above description, taken in connection with the accompanying drawing, the simplicity of the device, as well as the 80 advantages thereof will, it is thought, be perfectly apparent to those skilled in the art to which such invention appertains without further detailed description.

Having thus described the invention, what 85 I claim is:

The herein described construction of wrenches including, in combination, a stationary jaw having a toothed shank, a slideable jaw on the shank, said slideable jaw 90 having a longitudinal slot communicating with the toothed edge of the shank, a strip arranged longitudinally in the slot and having its end terminating away from the inner wall of said slot and secured to the side walls 95 of the said slot, said strip adjacent its inner end having its edge next to the shank provided with a transverse notch and its other edge formed with a round depression which is spaced from the said notch, a lever 100 loosely arranged in the slot and projecting therethrough, said lever adjacent its inner end having one of its edges notched and its other edge provided with a transverse rounded depression which is adapted to be 105 disposed to align with the rounded depression in the strip, a pivoted dog upon the inner end of the lever and adapted to play between the end wall of the slot and the 110 inner end of the strip and to co-act with the

teeth of the shank, a spring having a coiled portion disposed to be received in the alining rounded depressions in the lever and in the strip, the arms extending from the 5 coil of the spring having their ends bent whereby one of said ends will be received in the notch in the strip and the other end received in the notch in the lever to swing

the lever to normally force the dog into engagement with the teeth of the shank.

In testimony whereof I affix my signature in presence of two witnesses.

CHARLES McLAY.

Witnesses:

O. W. BRUNSELL,
PAWLO GLOWA.
